[57] CLAIM

The ornamental design for a table, as shown and described.

DESCRIPTION

FIG. 1 is a perspective view of one embodiment of my design;

FIG. 2 is a top plan view thereof;

FIG. 3 is a side elevational view thereof, the opposite side view being identical;

FIG. 4 is a front elevational view thereof, the rear elevational view being identical;

FIG. 5 is a top plan view of another embodiment of my design;

FIG. 6 is a side elevational view thereof, the opposite side view being identical;

FIG. 7 is a front elevational view thereof, the rear elevational view being identical;

FIG. 8 is a top plan view of still another embodiment of my design;

FIG. 9 is a side elevational view thereof, the opposite side view being identical; and,

FIG. 10 is a front elevational view thereof, the rear elevational view being identical.
